UNITED STATES PATENT OFFICE.

THEODORE A. MANCHESTER, OF LYNN, MASSACHUSETTS.

SHOE-NAIL CUTTER.

SPECIFICATION forming part of Letters Patent No. 314,255, dated March 24, 1885.

Application filed December 22, 1884. (No model.)

To all whom it may concern:

Be it known that I, THEODORE A. MANCHESTER, of Lynn, county of Essex, State of Massachusetts, have invented an Improvement 5 in Shoe-Nail Cutters, of which the following description, in connection with the accompanying drawings, is a specification, like letters on the drawings representing like parts.

In the manufacture of boots and shoes it 10 frequently happens that a lasting-tack or other nail is left protruding through the inner sole, to the injury of the foot and stocking; and to remove such nail is sometimes very troublesome, for the nail has to be bent and broken off 15 usually by the aid of a rasp, or by hammering on an iron last, which is but a temporary expedient, for it soon works up again.

The object of my invention is the production 20 of a tool which may be readily inserted within the boot or shoe, and by which the protruding nail or fastener may be cut off down close to or below the inner surface of the inner sole. My improved cutter has cutting-edges which are curved forward and upward from the under side of the tool, the cutting members being 25 curved both longitudinally and laterally, whereby they may be placed in operative position on any part of the boot or shoe from the heel to the toe.

Figure 1 represents a shoe in longitudinal section, and my improved cutter introduced 30 therein to cut off a tack or fastener left with its point above the inner sole. Fig. 2 is a top view of a part of my improved cutter; Fig. 3, 35 a section in the line $x-x$, Fig. 2, and Fig. 4 a section on the line $x'-x'$, Fig. 1.

My improved cutter is composed of two long arms or levers, a b , connected together by a

50 pivot-screw, c , about which and within a space, c' , between the two levers is placed a spring, c^2 , which acts normally to separate the levers. The cutting-edges of the cutter form parts of the jaws a' b' , connected with the arms a b , respectively, beyond the pivot c , the said cutting-edges starting from the lower side of 45 the jaws, and being extended forward and upward in a curve, as best shown in Figs. 1 and 3, and ending at or just above the level of the upper line of the jaws. The jaws are curved in cross-section, as best shown in Fig. 4, and the bevel of the cutting-edges is such that when the jaws a' b' are closed on the tack or nail to be cut, the edges will act to cut the nail flush with or a little below the surface of the inner sole.

55 The arms a b have projections a^2 b^2 , which are of proper length to meet just before the cutting-edges come together.

The long arms and very short jaws, and the peculiar curve given to the jaws, enable a nail 60 in any part of a boot or shoe from the shank forward to be cut off.

I claim—

As an improved article of manufacture, the herein-described cutting tool having the long 65 handles and the short jaws, the latter being curved, as shown and described, and having the curved cutting-edges to operate as set forth.

In testimony whereof I have signed my name to this specification in the presence of two sub- 70 scribing witnesses.

THEODORE A. MANCHESTER.
